UNITED STATES PATENT OFFICE.

CYRENIUS W. KUTZ, OF HUMBERT, PENNSYLVANIA.

TRACK STRUCTURE.

941,324.

Specification of Letters Patent.

Patented Nov. 23, 1909.

Application filed April 29, 1909. Serial No. 492,956.

To all whom it may concern:

Be it known that I, CYRENIUS W. KUTZ, a citizen of the United States, residing at Humbert, in the county of Somerset and State of Pennsylvania, have invented certain new and useful Improvements in Track Structures, of which the following is a specification, reference being had to the accompanying drawings.

10 This invention relates to improvements in track structures and more particularly to cross ties, track chairs and rail fastenings.

One object of the invention is to provide an improved metallic cross tie, chair or the like, which while especially adapted for use in mines, may be used for surface railroads.

Another object of the invention is to provide an improved track fastening which will permit of the removal of the rails from the ties, chair plates, etc. without entirely removing the fastenings from such ties or chair plates.

With the above and other objects in view, the invention consists of the novel features 25 of construction and the combination and arrangement of parts hereinafter fully described and claimed, and illustrated in the accompanying drawings, in which—

Figure 1 is a plan view of a portion of a 30 track especially adapted for use in a mine and embodying the present invention; Figs. 2, 3 and 4 are sectional views taken, respectively, on the lines 2—2, 3—3 and 4—4 in Fig. 1; Fig. 5 is an end view of one of the 35 ties; Fig. 6 is a plan view of the frog plate and the track fastenings thereon; Fig. 7 is a perspective view of one of the two-part rail clamping members or clips, the parts of the same being separated; Fig. 8 is an 40 inverted perspective view of a modified form of a two-part clip especially adapted for use between two rails which are disposed close to each other; and Figs. 9 and 10 are bottom perspective views of the two parts of another 45 form of clip adapted to use between two converging rails.

In the drawings 1 denotes the track rails of a main line, 2 the rails of a siding, 3 a V-shaped rail member arranged at the juncture 50 of two of the rails 1, 2 and 4 denotes guard or frog rails spaced from the pointed section 3 and formed by bending the ends of portions of the rails 1, 2; as clearly shown in Fig. 1. The parts 3, 4 are mounted on a metallic chair plate 5 while the rails 1, 2 are mounted on metallic cross ties 6. Each

of the improved cross ties 6 is stamped from a single piece of heavy metal and is of substantially rectangular-shape, its body portion or top 7 being flat and formed at its 60 longitudinal or side edges with depending flanges 8 inclined downwardly and outwardly and formed with corrugations or scallops 9, as shown in Figs. 1 and 5 of the drawings. The depending flanges 8 of the 65 ties are adapted to work down into the ground or road bed so that the top or body portions 7 of the ties lie flat upon the same, the peculiar shape of the flanges 8 causing them to effectively anchor the tie and prevent it from shifting either longitudinally 70 or transversely. By making the tie of metal, it will not rot as do wooden cross ties and it will be much more durable than such ties, and by making it as above described it will 75 be firmly anchored and will lie close to the bottom or floor of the mine passage and hence occupy much less space than the ordinary wooden cross tie. Since this improved metallic tie lies flat or flush with the floor 80 of the mine passage, it will not be necessary to fill the space between the rails and ties with gaub or culm as is customary when wooden ties are used in mines, thereby dispensing with the dust and dirt incident to 85 the use of such fillings for the track. The ties may be made long, as indicated at 6, or short, as indicated at 10, and the frog plate or chair 5 is constructed similar to the ties, as will be understood on reference to Figs. 90 1 and 5.

The track rails are adapted to be secured on the cross ties or chair plates by improved two-part clamp members or clips, the parts of which are designated by the numerals 11, 95 12. The parts 11, 12 of each clip are similar, each having a flat body portion of rectangular shape with one face at one end beveled, as shown at 13, and with an aperture 14 arranged adjacent to its other end. Said parts 100 11, 12 are superposed with the apertures 14 in alignment for the reception of a fastening bolt 15, which latter also passes through an opening 16 in the tie or chair plate. One or more of said openings 16 are provided on 105 each side of the rail and they are square or of polygonal-shape in cross section to receive the squared or flat faced portions 17 on the heads 18 of the bolts 15. Said bolts are passed upwardly through the tie and parts 110 or sections 11, 12 of the clip and on their projecting threaded extremities are applied

nuts 19 which when tightened clamp the clip sections or parts 11, 12 upon each other and upon the tie and base flange of the track rail, as clearly shown in Fig. 3 of the drawings. By making the parts or sections 11, 12 similar they may be reversed so that the beveled face 13 of either one may overlie and engage the upper face of one of the base flanges of the T-shaped track rails.

10 A further advantage of making the clips in two parts or sections 11, 12 is that when the nuts 19 are loosened the uppermost parts may be turned out of engagement with the base flanges of the rails, thereby permitting 15 the latter to be lifted from the ties or chair plates without entirely removing the clips or their fastening bolts. The clips above described are used for fastening the usual rails to ordinary ties or chair plates but 20 when the rails are of peculiar shape the especially shaped clip parts shown in Figs. 8, 9 and 10 are employed. In Fig. 8 the clip parts or sections 11^a, 12^a are so shaped as to engage and secure the adjacent base 25 flanges of two rails which are disposed close to each other, as, for instance, the pointed rail member 3 and the frog member 4. The part 12^a is adapted to enter between the opposing edges of the base flanges of the rail 30 members 3, 4 while the part 11^a is placed upon it and has the two beveled faces 13^a at its ends engaged with the upper faces of the base flanges of said rail members 3, 4, as will be readily understood on reference to Fig. 35 4. The parts or sections 11^b, 12^b of the clip shown in Figs. 9 and 10 are so shaped as to effectively secure two converging rails on a cross tie or chair plate, as will be understood on reference to Fig. 1. The part 12^b 40 has a V-shaped end adapted to enter between and engage the opposing edges of the base flanges of converging rails and the part 11^b, which is V-shaped has the under faces of its converging longitudinal edges beveled, as at 45 13^b, to engage the upper faces of the base flanges of such converging rails. Said part or section 11^b is formed with a longitudinal slot 14^b which receives the clamping bolt and which permits said part 11^b to be re- 50 tracted out of engagement with the base flanges of the rails when the clamping bolt is loosened for the purpose of removing the rail or rails from the tie, chair plate or the like.

55 Having thus described the invention what is claimed is:

1. The combination of a cross tie, a rail thereon, adjustable fastenings carried by the tie and two-part clips on said fastenings, 60 the lower parts of the clips being adapted to engage the edges of the base flanges of the rail, and the upper parts being adapted to engage the upper faces of the base flanges of the rail, said upper parts being also re- 65 tractable when the fastenings are loosened to permit of the removal of the rail from the tie without the removal of the clips therefrom.
2. The combination of a rail supporting plate formed from metal and having a flat top provided with an aperture and also having integrally formed zigzag shaped angular flanges projecting downwardly and outwardly from the edges of said top and adapted to enter the ground to anchor the 70 flat top upon the surface of the same, a non-rotatable fastening in the aperture of said plate and having a threaded upper end, track rails having base flanges resting upon said plate, a two-part clip arranged on said 75 fastening, the lower part of the clip being engaged with the edge of the base flange of the rail and the upper part of the clip being formed with a longitudinal slot to receive said fastening and being adapted to rest 80 upon the upper face of the base flange of the rail and a nut upon the upper threaded end of said fastening.
3. The combination of a plate, converging rails arranged on said plate, means on the 90 plate to engage the outer base flanges of the rails, a fastening projecting upwardly from the plate between the rails, a two-part clip arranged on the fastening, the lower part of the clip being engaged with the edges of 95 the inner base flanges of the rails and the upper clip part being angular in shape to engage the upper faces of the inner base flanges of the rails, said upper clip part being also formed with a longitudinal slot, 100 whereby it may be retracted on said fastening when the latter is loosened.
4. The combination of a rail-supporting plate formed from metal and having a flat top provided with apertures having flat 105 walls, said plate also having integrally formed zigzag shaped flanges projecting downwardly and outwardly from the edges of said top and adapted to enter the ground to anchor the flat top upon the surface of 110 the same, bolts having threaded upper ends and also ends formed with heads and shoulders, the latter being arranged in said flat walled apertures, track rails having base flanges resting upon said plate, two-part 115 clips arranged on said bolts and having their lower parts engaged with the edges of the base flanges of the rail, and the upper parts of said clips being engaged with the upper faces of the base flanges of the rail, and 120 clamping nuts upon the projected threaded ends of said bolts.

In testimony whereof I hereunto affix my signature in the presence of two witnesses.

CYRENIUS W. KUTZ.
